Primary Examiner — Eric Goodman*Assistant Examiner* — Amy Wierenga(74) *Attorney, Agent, or Firm* — Eckert Seamans Cherin & Mellott, LLC; David C. Jenkins**CLAIM**

The ornamental design for a panel with basket weave design, as shown and described.

DESCRIPTION

FIG. 1 is an isometric view of a panel with basket weave design;

FIG. 2 is a top plan view thereof;

FIG. 3 is a front view thereof;

FIG. 4 is a rear view thereof;

FIG. 5 is a left side elevation view thereof; and,

FIG. 6 is a right side elevation view.

The reverse side of the panel with basket weave design is not claimed. The broken lines representing the reverse side of the panel with basket weave design form no part of the claimed design.
